UNITED STATES PATENT OFFICE.

JAMES E. SEELEY, OF LOS ANGELES, CALIFORNIA. ASSIGNOR TO HIGH FREQUENCY IGNITION COIL COMPANY, OF LOS ANGELES, CALIFORNIA, A CORPORATION OF CALIFORNIA.

MAGNETO.

1,017,597.

Specification of Letters Patent. Patented Feb. 13, 1912.

Application filed January 31, 1911. Serial No. 605,775.

To all whom it may concern:

Be it known that I, JAMES E. SEELEY, a citizen of the United States, residing at Los Angeles, in the county of Los Angeles and State of California, have invented a new and useful Magneto, of which the following is a specification.

This invention relates to magnetos for use in connection with sparking systems, for example, in internal combustion engines, and the main object of the invention is to provide a magneto in which electromotive force will be generated effectively throughout a large range, thereby permitting a correspondingly large range for advancement of the spark. In order to provide for such operation, the armature according to the present invention is laminated in planes parallel to the axis of rotation, and the invention is directed particularly to means for the construction of an armature in this manner while providing effective and rigid support and connection of the several parts of the armature.

Other objects of the invention will appear hereinafter.

The accompanying drawings illustrate the invention, and referring thereto: Figure 1 is a longitudinal vertical section of the lower portion of the magneto embodying the invention. Fig. 2 is a transverse section of the magneto on line x^2-x^2 in Fig. 1. Fig. 3 is a perspective of the armature core.

1 designates the base of a magneto, 2 the field magnets thereof, and 3 the pole pieces secured to said field magnets and to the base, and embracing the armature.

The armature comprises heads or end members 5 and 6, means for rotatively supporting said heads, a core 7 and pole pieces 8 connecting said heads. The head 5 may consist of a disk having a hub 9 secured to a shaft 10, said shaft being mounted by bearing 11 in a fixed head 12 on the end of the base, and said shaft being provided with means indicated at 13 for connection to the driving means. Head 6 is secured to a sleeve or hollow shaft 4, through which passes the conductor 19 for connection to the usual current connecting means not shown, said connector being insulated by insulating sleeve 14. Said hollow shaft 4 is journaled by bearing 15 in a head 16 at a corresponding end of the base.

The core 7 of the armature consists of a plurality of plates or laminations 7', said plates extending in planes parallel to the axis of rotation of the armature. Said plates are preferably H-shaped having a contracted middle portion 17 and extended outer portions or extensions 18 at each end to enable the winding indicated at 20, to be wound on said central portion, and between said extensions. Said core may be retained in place by seating or fitting of said extensions in notches 21 in flanges 22 on the heads 5 and 6. The pole pieces 8, which are formed as segmental plates, fit over said flanges and core, and are held in place by screws indicated at 23, said pole pieces holding the core from transverse displacement and also connecting the heads 5 and 6 together.

The pole pieces 8 are of sufficient circumferential or angular extension to enable them to span the space 24 between the pole pieces 3 of the field magnet. Good results may be obtained by making the angular extension of the armature pole pieces about 88° and the angular extension of the field magnet pole pieces about 110° , giving an overlap of, say 18° . With such construction of the pole pieces, I have found that effective electromotive force is generated in the armature throughout a range of substantially 75° . An important feature contributing to this result is the arrangement of the laminations in planes parallel to the axis of rotation as distinguished from transverse to said axis. With laminations in planes transverse to the axis of rotation, the lines of force through the core tend to concentrate along lines of minimum length, so that when the lines are entering the armature pole piece at one edge and leaving the opposite armature pole piece at the opposite edge, the lines of force will pass through the core in an oblique direction; this being under such conditions, the period of maximum electromotive force in the circuit, as the magnetic flux is then changing most rapidly. But with the laminations parallel to the axis of rotation, the lines of force are not permitted to cross obliquely through the core, but substantially follow the laminations, so that when the armature pole pieces are in the positions referred to, the core offers a greater reluctance by reason of the distortion of the

magnetic lines of force, than when the armature pole pieces are directly opposite the field pole pieces so as to allow the magnetic flux to pass through the laminations without distortion and, therefore, with minimum resistance. The effect of this is to increase the magnetic flux continuously, and more or less uniformly from the time when the forward edge of the armature pole piece comes under the rear edge of the field pole piece to the time when the armature pole pieces are directly opposite the field pole pieces, this continuous or substantially uniform rate of increase of magnetic flux resulting in a continuous generation of electromotive force of effective magnitude throughout a considerable range of angular motion.

What I claim is:

In a magneto, the combination with the field pole pieces of an armature, mounted to rotate between said pole pieces, and comprising heads having opposite notches, a core consisting of H formed laminations, having arms extending into said notches to secure the laminations in place, and segmental pole pieces secured to said flanges, and extending over and in contact with said core.

In testimony whereof, I have hereunto set my hand at Los Angeles, California this 24th day of January 1911.

JAMES E. SEELEY.
